Patented Nov. 15, 1921.

August E. Fraass, Inventor
By his Attorney
Max S. Drummey

UNITED STATES PATENT OFFICE.

AUGUST E. FRAASS, OF NEW ROCHELLE, NEW YORK.

DESIGN FOR A SUCTION-BULB.

59,646.

Specification for Design.

Patented Nov. 15, 1921.

Application filed November 20, 1920. Serial No. 425,583. Term of patent 7 years.

To all whom it may concern:

Be it known that I, AUGUST E. FRAASS, a citizen of the United States of America, residing at New Rochelle, in the county of Westchester and State of New York, have invented a new, original, and ornamental Design for a Suction-Bulb, of which the following is a specification, reference being had to the accompanying drawing, forming part thereof.

The figure is a side elevation of the suction bulb showing my new design.

I claim:

The ornamental design for a suction bulb as shown.

In testimony whereof I have affixed my signature in presence of two witnesses.

AUGUST E. FRAASS.

Witnesses:

WERNER MUELLER,

WALTER BOLLMANN.
